Inventor.

Zelma Ritter von Wessely.

United States Patent Office.

ZDEUKO RITTER VON WESSELY, OF NEW YORK, N. Y., ASSIGNOR TO PROVIDENCE TOOL COMPANY, OF PROVIDENCE, RHODE ISLAND.

Letters Patent No. 92,673, dated July 13, 1869.

IMPROVEMENT IN BREECH-LOADERS.

The Schedule referred to in these Letters Patent and making part of the same.

To all whom it may concern:

Be it known that I, ZDEUKO RITTER VON WESSELY, civil engineer, of 48 Pine street, New York city, have invented certain new and useful Improvements in Breech-Loading Fire-Arms, of which the following is a full, clear, and exact description.

My invention relates to that class of breech-loading fire-arms, in which the breech-block is pivoted to move vertically on a horizontal axis, at or near the back end of the breech-block.

The object of the first part of my invention is to dispense with the outside hammers and side locks heretofore usually employed, and to render the gun self-cocking; and the improvement consists,

First, in a novel method of combining a vibrating breech-block, a vibrating hand-lever, and a vibrating hammer, working on the same pivot as the hand-lever, and moving in a recess in the breech-block, in such manner that both the hand-lever and breech-block co-operate in cocking the gun.

Second, my improvement further consists in a novel method of constructing a breech-block with a recess in its under surface, curved eccentrically to the arc described by the head of the hammer, and bearing upon said head, so that in the act of opening the breech the cocking of the hammer is completed by the action of the inclined recess on its head.

Third, the improvement further consists in a novel method of combining a vibrating breech-block, a vibrating hammer, a vibrating hand-lever, operating both the breech-block and hammer, a main-spring on the hand-lever, and a vibrating sere, which also acts as a trigger, which holds the hammer at full cock, while the main-spring is being compressed by the hand-lever in closing the breech.

Fourth, my invention further consists in a novel method of combining a vibrating breech-block, a reciprocating striker, held within the breech-block by a spring, to prevent accidental explosions in closing the breech; a hammer, vibrating in a recess in the breech-block, and a main-spring mounted on a vibrating hand-lever. By this mode of construction, the accidental discharge of the arm is effectually prevented, for were the trigger pulled while the breech was opened, the main-spring would merely lift the breech-block slightly, and then allow it to drop quickly before the hammer could strike the striker.

The object of the next part of my invention is to prevent the main-spring from forcing the hammer out of place when the pin, which secures the hammer and hand-lever to the frame, is removed; and the improvement consists,

Fifth, in a novel method of mounting the main-spring on a hand-lever, vibrating on a common centre with a

hammer with which it is connected by a tubular pivot, through which the pin which secures the hand-lever to the frame passes, so that when the pin is removed, the lever, spring, and hammer may be detached from the frame without being separated from each other.

The object of the next part of my invention is to enable the hammer to strike the striker with force sufficient to ignite the cartridge, and then quickly to retract the hammer out of the way of the striker, in order that the latter may be retracted into the breech-block; and the improvement consists,

Sixth, in a novel method of combining a vibrating breech-block, a reciprocating striker and its retracting-spring, with a vibrating hammer, a main-spring, and an adjustable stop on the hand-lever, to limit the forward movement of the hammer.

The object of the next part of my invention is to prevent accidental explosions, by pulling the trigger, when the breech is closed, and the gun at full cock; and the improvement consists,

Seventh, in a novel method of combining with the trigger a horizontally-vibrating stop, interposed between the stock and trigger, to prevent the pulling of the latter.

In the accompanying drawings I have shown all my improvements as embodied in one arm. It is obvious that some parts of my invention might be used without the others, or adapted to arms differing in construction from that herein shown.

Figure 1 represents a plan or top view of so much of a gun embracing my improvements as is necessary to illustrate my invention.

Figure 2, a vertical longitudinal central section through the same, with the parts in the position they occupy immediately after firing.

Figure 3, a similar view of the same, with the breech open.

Figure 4, a vertical transverse section through the gun, in the line of the rear end of the barrel, looking toward the front, showing the details of the extractor.

Figure 5, a plan or top view, with the breech-block removed, showing the sere, hammer, and hand-lever.

Figure 6, a plan of the under side of the breech-block.

Figure 7, a plan of the under side of the stock, showing the safety-stop for the trigger.

Figure 8, a vertical longitudinal section, showing a modification of the striker or firing-pin, and the method of retracting the hammer, after firing, by the main-spring.

In order to carry out my invention, I connect the barrel, A, of the gun with the frame or body, B, in any proper well-known way, and in like manner connect this body with the stock C.

In order to adapt my gun to the use of long cartridges, I mount the breech-block, D, on a pivot, d, on the frame. The centre of this pivot coincides with the axis of the bore of the gun, as shown by the red line in figs. 2 and 3, instead of placing the pivot above the line of the bore, as heretofore. I likewise hollow out the groove *a* in the top of the breech-block, more than usual. I am thus enabled readily to insert long cartridges.

A striker, e, slides endwise in a longitudinal slot in the breech-block.

A spiral spring, *e*¹, encircling this striker, keeps it within the breech-block, when not protruded by the hammer, while a stop, *e*², on the striker, prevents it from being retracted too far.

A hand-lever, F, which, in this instance, and by preference, serves as a trigger-guard also, is pivoted to the frame B, by a pin, f. The rear end of this guard is held up when required by a spring-catch, f', of the form shown in the drawings.

A hammer, G, is arranged between the jaws of the hand-lever, and moves on the same pivot with it.

The main-spring H is inserted in a groove in the hand-lever, and held there by the lever overlapping its doubled end, as shown in figs. 2 and 3.

One leaf of this spring rests on the lever, while the other bears against the rear side of the hammer. The main-spring and hammer are thus free to vibrate with the hand-lever.

In order that the spring may not force the hammer out of its position in the lever when the parts are detached, I unite the lever and hammer by a thimble, or collar, g, shown in red in figs. 2 and 3, and in dotted lines in fig. 5.

The length of this thimble is equal to the width of the lever, and the lever and hammer both turn freely on it.

The pin f, which unites the lever to the body, passes through this thimble; consequently, when the pin is removed, the hand-lever, hammer, and spring may be removed without separating them from each other, as they are held together by the spring.

Arms F', on the lever, take into notches in the under side of the breech-block, in order to move it up and down.

The hammer G vibrates between these arms.

A hook, g¹, on the hammer, embraces the under side of the hand-lever F; consequently, as the lever is depressed, the head of the hammer is retracted at the same time that the breech-block is depressed to open the breech.

As the hammer and the hand-lever move through corresponding arcs at equal distances from the centre, the breech could not be depressed below the line of the bore, without moving the lever an inconvenient distance.

To obviate this difficulty I form a curved recess, g², in the under side of the breech-block, in which recess the head of the hammer works. The curve of this recess, it will be observed, is eccentric to the pivot of the hammer.

When the lever F is depressed, the hammer is first acted upon by the lever, and then by the curve of the recess, which forces the hammer down, until its notch is caught by a sere, I, of an elbow-lever form, pivoted at i, and acted upon by a sere-spring, i¹. The sere terminates in a trigger, i².

It will thus be seen that the hammer is held at full cock while the lever F is depressed; consequently the main-spring is not compressed, and its tension on the hammer is diminished.

When the breech is closed, the main-spring is compressed to its full tension, and the gun is fired by releasing the sere from the hammer.

Should the trigger be pulled when the breech is open, the spring would merely lift the block slightly, and it would drop quickly again without the hammer hitting the striker.

In fig. 2 it will be seen that the parts are so arranged that the hammer does not touch the breech-block until the latter is depressed.

In order that the hammer may retract quickly after hitting the striker, I secure an adjustable screw-plate, h, on the hand-lever, above the main-spring, as shown in red in figs. 2 and 5.

The elasticity of the main-spring is sufficient to carry its front upper leaf, which bears against the hammer, far enough beyond the plate h to fire the charge, and the resilience of the spring quickly retracts the hammer after hitting the striker.

The range of motion of the hammer can be varied by adjusting the plate h higher or lower.

In order to prevent accidental explosions when the gun is cocked and the breech closed, I pivot a wedge, k, under the stock, so that it may be interposed between the trigger and stock, and thus prevent the hammer from being released by an accidental pull on the trigger.

The tendency of the main-spring in my gun is constantly to open the breech whenever the catch f is released.

The catch thus not only holds the trigger-guard in place, but also keeps the breech closed.

An extractor, L, shown in figs. 2, 3, and 4, vibrates on a pivot, l, to extract the cartridge, and is moved by the vibration of the breech-block striking its toe, l', in its descent, as is well understood.

In fig. 8, I have shown a method of working the striker directly from the hammer, without the use of an independent recoil-spring, and also a method of retracting the hammer, after striking the striker, by the main-spring itself, by causing a part of the lower leaf of the main-spring to strike a stop on the hook g¹ of the hammer.

What I claim as my invention, and desire to secure by Letters Patent, is—

1. The combination of the vibrating breech-block with the vibrating hand-lever and the vibrating hammer, the two latter working on a common pivot; the combination being and operating substantially as set forth.

2. The combination, substantially as set forth, with the hammer, of the eccentrically-recessed vibrating breech-block, which recess causes the cocking of the hammer to be completed by the opening of the breech.

3. The combination of the breech-block, hammer, hand-lever, main-spring, and sere, the combination being and operating substantially as set forth.

4. The combination of the sliding striker, recoil-spring, recessed breech-block, vibrating hammer, main-spring, and hand-lever, the combination being and operating substantially as set forth.

5. The combination of the hand-lever, main-spring, and hammer, with the collar g and solid pin f, as set forth.

6. The combination of the breech-block, striker, and recoil-spring, with the hammer, the main-spring, and its adjustable stop h, as set forth.

7. The combination of the trigger with the stop-wedge, operating as set forth, to prevent accidental explosions.

In testimony whereof, I have hereunto subscribed my name.

ZDEUKO RITTER VON WESSELY.
